MACHINE FOR MANUFACTURING
FIBERBOARDS

Nils Ryberg, Stockholm, Sweden

Application August 31, 1948, Serial No. 47,060

8 Claims. (Cl. 154—1)

1

The present invention relates to a machine for manufacturing a building element in the shape of a board made from straw or a similar long fibred vegetable material.

A preferred form of machine to which the invention is applied comprises an open-ended channel of a cross section corresponding to the desired cross section of the board to be manufactured, a hopper supplying measured (pre-determined or exactly dimensioned) quantities of the fibrous raw material into said channel at one end of the same, and a plunger reciprocating in the inlet portion of said channel for compacting and gradually feeding the measured quantities of raw material through the channel, wherein the measured quantities are step-wise compacted and combined to a continuous board or web during drying the same and a coating material is applied to and glued to each surface of the continuous board or web, this web then being cut to fibrous boards (elements) of the desired length.

The main object of the invention is to create such a machine of the type set forth above, that the material may, in the individual zones of treatment, be subjected to conditions which as far as the temperature is concerned are completely independent of each other, and thereby will allow compacting, web-forming and coating at the respective proper temperature, whereby the production of straw boards and similar boards of a high quality is secured by simple means.

A related object of the invention is to secure a positive supply of the measured quantities of the raw material at the correct point of time in relation to the reciprocal movement of the piston, as well as an exactly timed cutting of the individual quantities of straw or the like by the piston in co-operation with a stationary knife.

With these and other objects in view the invention comprises the novel features and combination of features set forth in the following description and specifically pointed out in the annexed claims.

In the accompanying drawings a preferred form of a machine embodying the invention is shown as an example. In the drawings:

Fig. 1 is a substantially diagrammatic longitudinal section of the machine,

Fig. 1a and Fig. 1b are side elevations of the raw material feeder shown in different phases of motion in order to illustrate its action,

Fig. 2 is a side elevation on a larger scale, with

2

parts removed, of a mechanism for guiding the plunger in front of the compacting channel.

Fig. 3 is a plan view of the mechanism shown in Fig. 2, with parts removed,

Fig. 4 is a cross section on the line IV—IV of Fig. 1 through a non-heated section of the compacting channel on a larger scale,

Fig. 5 is a cross section of a slight modification of the fastening device shown within the encircled portion of Fig. 4 on a still larger scale,

Fig. 6 is a cross section on the line VI—VI of Fig. 1 through the drying channel on a larger scale, and

Fig. 7 is a longitudinal section of a portion of the compacting channel in order to show the means for preventing backward movement of the raw material upon the return stroke of the plunger.

Hereinafter the main elements of the machine as diagrammatically illustrated in Fig. 1 will first be described.

According to the main feature of the invention the open-ended channel comprises three separate sections. The first section constitutes the compacting chamber proper, in which a measured quantity of straw or the like is compacted, preferably at normal temperature. The second section is a heated, binding and web-forming pressure chamber, in which the compacted bodies obtained from the first compacting chamber is step-wise combined with the preceding compacted body to a flat web during heating to a temperature allowing the binding or adhesive effect of the natural adhesives contained in the straw or other fibrous material to release. The third section is a heated coating chamber, in which onto each side of the straw web a coating web together with an adhesive is applied during heating to the binding temperature of the adhesive as applied, the internal cross-section of said chamber being adjustable to allow for coatings of different thicknesses.

According to a related feature in a machine as characterized above a positively operated feeder is provided at the inlet of the first compacting chamber, which feeder, when the piston is retracted, positively supplies a measured quantity of straw material or the like from the hopper into the first compacting chamber, and a knife is provided, against which the piston when performing its working stroke cuts the measured quantity of straw or the like, then the web leaving the coating chamber being cut to pieces of desired length.

The machine is supported by a frame which

for erection purposes may comprise two or more sections as indicated. Mounted in said frame near the top thereof is a set of lower and upper working table sections, provided at a certain vertical distance from each other so as to form a longitudinally extending series of horizontal channels between themselves, viz. a first compacting channel section 2 formed by lower and upper table sections 21 and 22, respectively, a second compacting channel section 3 formed by lower and upper table sections 31 and 32, respectively, and a surface coating and drying channel 4 formed by lower and upper table sections 41 and 42, respectively. The lower table section 21 of the first compacting section 2 projects beyond the front (left hand) end of the respective upper table section 22 so as to form a support for the compacting plunger 5 in front of the inlet of said channel as represented by the space between the said left hand end of table section 22 and the upper surface of table section 21. The plunger 5 is reciprocated on said projecting portion of the lower table section 21 into and out of channel section 2 by power derived from a motor 6 by a transmission mechanism to be hereinafter more nearly described and is guided during this movement by antifriction rollers which will also be hereinafter described.

Provided above the projecting portion of the lower table section 21 of the compacting channel 2 is a hopper 7 the lower end of which is situated slightly above the level of the lower surface of the upper table section 22 immediately in front of the fore end thereof. Said hopper extends transversely over the entire width of the plunger so as to be capable of supplying the fibrous raw material along the entire width of the inlet of the compacting channel 2. Provided adjacent, that is, in front of, the lower portion of hopper 7 is a feeder driven from motor 6 in a way to be hereinafter described, said feeder comprising a set of pins or fingers 8 forming a comb-like structure which extends over the entire width of the hopper. Said pins are adapted to enter the lower portion of the hopper through a series of slots 9 formed in the front wall of the hopper, one for each pin.

Between the non-heated compacting channel section 3 a heat insulation 30 (Fig. 7) is provided. The channel section 3 and the surface coating and drying channel 4 are spaced from each other by a sufficient amount for allowing the introduction of a surface coating material to either surface of the compacted board while passing from channel 3 to channel 4. In Fig. 1 a lower web of surface coating material is indicated at 10 and an upper web of such material is indicated at 11. Each web is taken from a reel 12 or 13, respectively, and each web is guided by a series of rollers 14 and 15, respectively. In order to prevent the webs from becoming slack each of them is loaded by a loose roller 16 or 17, respectively, supported by a bight of the respective web between a pair of guide rollers 14 or 15, said loose roller being loaded by a weight, not shown, which is represented by an arrow in the drawing. In connection with the webs 10 and 11 means, not shown, are provided for applying a layer of a suitable binding agent to the surfaces of the webs facing the board. Provided in the extension of the surface coating channel 4 is a set of rollers 18 for supporting the finished board as it emerges from channel 4. In connection with the supporting path as formed by said rollers 18 a cutting mechanism is provided to cut off the con-

tinuous board to plates of any desired length. Such a cutting mechanism, however, is not shown in the drawing, because it may be of various designs.

In addition to the elements above described, Fig. 1 also shows a mechanism for adjusting the level of the lower table section 41 belonging to the surface coating channel 4 in order to allow the use of surface coating material of varying thickness. The mechanism as indicated in Fig. 1 for this purpose comprises a bed 19 sloping in the direction of movement of the board which is located below the table section 41 at a suitable distance therefrom, a wedge 20 tapering in the opposite direction which is inserted between the bed 19 and the table section 41, a set of antifriction rollers 23 between the bed 19 and the wedge 20, another set of antifriction rollers 24 between the wedge 20 and the table section 41, and a hand wheel 25 connected to the wedge 20 for effecting a displacement thereof longitudinally when it is desired to vertically adjust the table section 41.

The upper table section 22 of the first compacting channel 2 is provided with a transversely extending knife 26 at its fore end. The edge of this knife should be situated on a level with the lower surface of the table section 22. In order to allow an exact setting of the knife edge on said level, suitable adjusting means are provided, comprising, as indicated in Fig. 7, a series of adjusting screws 27 and a series of clamping screws 28. Immediately behind that point of channel 2 at which the fore end of the plunger is when the plunger reaches its right hand dead centre, means are provided in the table sections 21 and 22 for preventing the amount of raw material compacted at the respective working stroke of the plunger from moving backward upon the return stroke of the plunger. Such means may comprise a pair of toothed plates 29 let into the opposed surfaces of table sections 21 and 22, respectively. The teeth of said plates are designed like those of a ratchet wheel and so arranged as to allow a feeding of the raw material forward (to the right in the drawing) but blocking the material against backward movement (to the left).

The construction of the table sections 21 and 22 and their connection with the machine frame is illustrated in Fig. 4 which, as already mentioned, is a cross section through channel 2. Each table section 21 or 22 comprising a solid plate having longitudinally and transversely extending strengthening ribs 212 and 213, respectively, on their surfaces remote from each other. The fastening of the said plates to the frame 1 of the machine is effected by means of a series of bolts 214 on each side. Each bolt extends as reckoned from below through a lug 215 of frame 1, further through the lower plate 21, then through a distance member 216, which forms the respective side wall of the channel 2 and, finally, through plate 22. Below the lugs 215 the bolts are formed with integral heads and above the plate 22 the bolts have nuts screwed thereon to keep the entire structure together. The distance pieces 216 determine the height of the channel and, thus, the thickness of the board to be produced therein. In this fastening structure the lugs 215 may be subjected to heavy stresses due to the fact that the entire table structure is clamped thereto. In order to reduce the stresses on the lugs to those resulting from the weight of the table structure only, the fastening may be modified as indicated in Fig. 5, that is to say,

by inserting a distance tube 217 between the integral head of each bolt and the lower surface of the table section 21. The length of such tube 217 should be so chosen as to keep the head of the bolt at a slight distance from the lug 215, as indicated in Fig. 5.

The table sections 31 and 32 are constructed in the same way as the table sections 21 and 22 except for the transversely extending borings 34 (Fig. 7) to receive electric heating element. The table sections 31 and 32 are supported and clamped in the same way as are the table sections 21, 22. The table sections 41 and 42 are constructed in the same way as are the table sections 31, 32, thus also provided with transversely extending borings 44 (Fig. 1) to receive electric heating elements, and they are arranged in the same way as are the first-mentioned table sections, except for the feature that the lower section or plate 41 is vertically adjustable. Thus, the table sections 41, 42 are connected to a unit together with the distance pieces 316 (Fig. 6) and the adjusting elements 19, 20, 23, 24 by means of clamping bolts 314 pressing on the top surface of the side members of the table section 42.

As already mentioned, the plunger 5 is guided in front of the compacting channel 2 not only by the projecting portion of the lower table section 21 but also by a special guide mechanism in front of said table section. Said mechanism, which is diagrammatically indicated in Fig. 1 by the small circles 50 and 51, are shown in detail in Figs. 2 and 3. The guide mechanism comprises on each side of the machine a series of lower and upper guide rollers 50 and 51, respectively, for engaging the lower and upper surface, respectively, of the plunger, and a set of guide rollers 52 for engaging the longitudinal edge surfaces of the plunger. On opposite sides of the projecting portion of table section 21 the plungers are guided by lateral wall members 21^a and 21^b.

The transmission between the power motor 6 and the plunger comprises, in the example shown, a rope drive 60, a reducing gear 61 and a pair of connecting rods 62.

From the reducing gear power is also imparted to the feeder 8, Fig. 2. The set of fingers 8 are secured to a frame 80 rotatably mounted on the transverse shaft 81 which is connected by links 82 to arms 83 on a transverse shaft 84. Shaft 81 is driven by a chain transmission or the like 85 from an intermediate shaft 86 which in its turn is driven from the reducing gear by any desired type of transmission gear. Mounted on shaft 84 is a spring loaded stretching device 87 for the chain or the like 85. By the arrangement described for driving the feeder, the fingers 8 are caused to move from the position shown in Fig. 1 to the position shown in Fig. 1b during each return stroke of the plunger. As indicated in Fig. 1b the fingers project through the slots 9 into the hopper 7 to feed a portion of raw material through the outlet end of the hopper while the plunger is retracted so as to expose the lower end of the hopper. During the return stroke, the fingers 8 move outside the hopper to the position shown in Fig. 1 as indicated by the arrows in Fig. 1b. Thus, no feeding takes place during the working stroke, nor as long as the plunger is at rest.

As shown in Fig. 3 the operating end of the plunger 5 is shaped like a roof, formed as it is by two inclined surfaces 5^a and 5^b sloping from a point intermediate between the opposite sides of the plunger. The edge of the knife 26 is

straight and extends at right angle to the longitudinal direction of the channel, as indicated by the dotted line 26 in Fig. 3.

The guide rollers 50—52 may be provided with a surface of a character to secure a good contact with the plunger without effecting or deforming it. To this end the rollers may be provided with rings of rubber or the like projecting slightly outside the periphery of the otherwise metallic rollers.

The operation of the machine will, no doubt, sufficiently appear from the foregoing description. It is, therefore, considered sufficient hereinafter to recapitulate it in its general outline only.

The raw material, as straw, is introduced by hand or by suitable mechanical means to the hopper in a way so as to be distributed over the entire area of passage thereof. During the reciprocation of the plunger the feeding fingers 8 are moved in the peculiar way described above so as to feed a measured portion of raw material upon the projecting part of the table section 21 in front of the inlet of channel 2, substantially at the rear dead center of the plunger. Upon the following working stroke the plunger forces said portion of raw material in front of it into the channel 2, compacts it and leaves it forced against the previously compacted board, if any, in chamber 3. The toothed members 29 prevent the portion of raw material thus compacted from moving backward as the plunger commences its return stroke. Owing to the pressure as afforded by the compressed portion on the board in channel 3 the board is fed by small steps therethrough. While passing through channel 3 the board is heated sufficiently, say up to 150° C., for vaporizing the moisture contained therein, so that the board is substantially free from moisture when discharged from channel 3. While passing from channel 3 to channel 4 the board receives the webs of coating material 10 and 11. While passing through channel 4 the coating material is held against the surfaces of the board by a certain pressure which may be controlled by adjustment of the lower table section 41, so that the webs are caused to firmly stick to the board by the action of the binding agent. While passing through channel 4 the board and webs are subjected to a moderate heating, say 130° C., sufficient for causing the binding agent to set, so that the board when discharged from the channel 4 is in a finished state allowing its immediate use for building purposes. By a cutting device, not shown, the continuous board leaving the channel 4 is cut to pieces of any desired length.

What I claim is:

1. A machine for the manufacture of boards for building purposes from a long-fibred vegetable raw material comprising in combination a machine frame including upper and lower wall members for bounding an open-ended flat channel for receiving portions of said raw material at intervals, a plunger reciprocable into and out of said channel for introducing a portion of fibrous material at a time into the channel and compacting it therein as well as feeding it therethrough, a feed hopper for supplying the fibrous raw material onto said lower wall member in front of the inlet opening of said compacting channel, means in connection with said hopper for positively feeding a portion of raw material in said hopper towards said lower wall member during the return stroke of the plunger, a knife edge provided at the front end of said upper wall member 75 on a level with the lower surface of said wall

member for severing the portion of fibrous material in front of the plunger, when the operating end of the plunger reaches the inlet of the channel during its operating stroke, other upper and lower wall members provided in alignment with those of the compacting channel for constituting a channel for receiving the compacted material from the compacting channel, heating elements in said other upper and lower wall members for heating the compacted material between said wall members to a sufficiently high temperature for causing the natural binding substances of the fibrous material to act as a binding agent between the fibers, a third set of upper and lower wall members for constituting a channel in rectilinear extension of the next preceding channel, heating means in said third set of upper and lower wall members, means in front of said third set of wall members for applying a web of flexible material to the upper and lower surfaces of the compacted fibrous mass while passing between the second set of wall members and the third set of wall members, and means for adjusting the position of the lower wall member of the third set of upper and lower wall members in the vertical direction with respect to the upper wall member for changing the thickness of the fibrous product passing therebetween.

2. A machine for the manufacture of boards as claimed in claim 1, and in which the compacting channel is provided with means for retaining the compressed portion therein as the plunger commences its return stroke.

3. A machine for the manufacture of boards as claimed in claim 1, and in which the non-heated compacting channel and the heated shaping channel are heat insulated with relation to each other.

4. A machine for the manufacture of boards as claimed in claim 1, characterized by the provision of means for adjusting the position of the

knife to maintain its edge on a level with the respective surface of the compacting channel.

5. A machine for the manufacture of boards as claimed in claim 1, characterized by the provision of means for guiding the plunger in front of the inlet end of the compacting channel.

6. A machine for the manufacture of boards as claimed in claim 1, and in which interconnecting means are provided for reciprocating the plunger and controlling the operation of the feeding means in a timed relation to each other.

7. A machine for the manufacture of boards as claimed in claim 1, and in which exchangeable side walls are provided for the various channels.

15 8. A machine for the manufacture of boards as claimed in claim 1, and in which exchangeable side walls are provided for the various channels which comprise a pair of longitudinally extending distance pieces clamped between side members of the respective lower and upper working table sections.
